[57] CLAIM

The ornamental design for a garage door, as shown and described.

DESCRIPTION

FIG. 1 is a front elevation view of a garage door showing my new design;

FIG. 2 is a rear elevation view thereof;

FIG. 3 is an end elevation view thereof;

FIG. 4 is a top view thereof;

FIG. 5 is a bottom view thereof;

FIG. 6 is a vertical sectional view taken along lines 6—6 of FIG. 1;

FIG. 7 is a horizontal sectional view taken along lines 7—7 of FIG. 1;

FIG. 8 is a front elevation view of another form of garage door showing my new design;

FIG. 9 is a rear elevation view thereof;

FIG. 10 is an end elevation view thereof;

FIG. 11 is a top view thereof;

FIG. 12 is a bottom view thereof;

FIG. 13 is a vertical sectional view taken along lines 13—13 of FIG. 8; and

FIG. 14 is a horizontal sectional view taken along lines 14—14 of FIG. 8.
